COMBINATION VALVE AND STRAINER

Merlyn R. Truesdell, Sioux City, Iowa, assignor to Century Engineering Corporation, Cedar Rapids, Iowa, a corporation of Iowa

Filed Nov. 8, 1968, Ser. No. 14,367

Term of patent 14 years

Int. Cl. D23—01

U.S. Cl. D23—20

FIG. 1

FIG. 2

FIG. 3

FIG. 1 is a side elevational view of my design for a combination valve and strainer;

FIG. 2 is another side elevational view thereof; and

FIG. 3 is a top plan view thereof.

My design resides in the portions shown in full lines in the drawings.

I claim:

The ornamental design for a combination valve and strainer, substantially as shown and described.
